UNITED STATES PATENT OFFICE.

MORTIMER L. PACKER, OF COLUMBUS, OHIO.

DESIGN FOR A GAS-HEATER.

60,057.

Specification for Design.

Patented Dec. 20, 1921.

Application filed February 7, 1921. Serial No. 443,280. Term of patent 7 years.

To all whom it may concern:

Be it known that I, MORTIMER L. PACKER, a citizen of the United States, residing at Columbus, in the county of Franklin and State of Ohio, have invented a new, original, and ornamental Design for Gas-Heaters, of which the following is a specification, reference being had to the accompanying drawing, forming part thereof.

The figure is a front elevation of a gas heater, showing my new design.

I claim:

The ornamental design for a gas heater, as shown.

MORTIMER L. PACKER.
